UNITED STATES PATENT OFFICE

166,962

TABLE LAMP BASE

Sidney G. Goforth, Sr., Memphis, and Sidney G. Goforth, Jr., Millington, Tenn.

Application March 18, 1952, Serial No. 18,944

Term of patent 14 years

(Cl. D48—20)

To all whom it may concern:

Be it known, that we Sidney G. Goforth, Sr., and Sidney G. Goforth, Jr., both citizens of the United States, residing, respectively, at Memphis, in the county of Shelby, and State of Tennessee, and at Millington, in the county of Shelby, and State of Tennessee, have invented a new, original, and ornamental Design for a Table Lamp Base, of which the following is a specification; reference being had to the accompanying drawings, forming a part thereof.

The dominant features of our design reside in the portions shown in full lines.

We claim:

The ornamental design for a table lamp base, as shown and described.
